UNITED STATES PATENT OFFICE.

JULIAN KENNEDY, OF PITTSBURG, PENNSYLVANIA.

VALVE FOR BLOWING-ENGINES.

SPECIFICATION forming part of Letters Patent No. 552,909, dated January 14, 1896.

Application filed March 15, 1895. Serial No. 541,935. (No model.)

To all whom it may concern:

Be it known that I, JULIAN KENNEDY, of Pittsburgh, in the county of Allegheny and State of Pennsylvania, have invented a new 5 and useful Improvement in Valves for Blowing-Engines, of which the following is a full, clear, and exact description, reference being had to the accompanying drawings, forming part of this specification, in which—

10 Figure 1 is a vertical longitudinal section of a blowing-engine cylinder provided with my improved valve system. Fig. 2 is an end elevation of the piston-head, showing one of the valves in cross-section. Fig. 3 is a top 15 plan view of the cylinder; and Fig. 4 is a view similar to Fig. 1, showing a modification.

My invention relates to the valves employed in pneumatic cylinders—such as blowing-engines, air-compressors, refrigerating apparatus, &c.—and is designed to do away with the disadvantages consequent to the use of the present types of valves.

In blowing machinery, where the valves are of the gridiron type, they are unbalanced and 25 considerable power is necessary to move them. As they must be moved quickly and with intermittent motions, severe shocks and strains are set up in the valve-gear. In former valves of the piston type, in which the above-30 named disadvantages are not present, a large amount of clearance was necessary in the operating-cylinder. These evils are entirely done away with by my invention.

In the drawings, in which like numerals 35 indicate like parts, 2 represents a blowing-cylinder, having therein the piston 3, whose piston-rods 4 are actuated by a suitable motive cylinder. Through the head of the piston 3 pass two tubular valves 5 and 6, which 40 are open at both ends and are surrounded by suitable packing-rings, as shown, where they pass through the piston and the cylinder-heads. Each valve is reciprocated independently of the piston by means of the valve-45 stems 7, which in turn may be actuated by eccentrics or by other mechanism. There are also near its ends annular bridged ports 8, 9, 10, and 11, the ports 8 and 9 being in the inlet-valve 5, while the ports 10 and 11 are located in the outlet-valve 6. The outlet-valve 50 is considerably longer than the inlet-valve,

and its ends are cased in by projecting end pockets 12, which communicate with the common offtake 13 leading to the reservoir.

14 are tubular stays for the valve casings 55 or pockets.

The action is as follows: As the piston moves upward in the direction of the arrow, it is forcing air through ports 10 into the valve 6 and therethrough into the reservoir. 60 At the same time it is drawing in air upon the other side through the open ends of the valve 5 and the ports 9. As the piston nears the end of its stroke, the valve 5 is moved down and the valve 6 is moved up, and as it reaches 65 the end of its stroke the valve 5 reaches its mid-position and both ports 8 and 9 are shut off, while the valve 6 has moved up to such point as to close the outlet-port 10. As the piston begins to move down, the valve 5 is 70 also moved down and air enters behind the piston through the port 8. The outlet-valve, however, being longer and thus provided with inside lap, has not yet reached the point where the ports 11 communicate with the interior 75 of the cylinder, and hence the piston compresses the air in the cylinder to or about the pressure of the reservoir before the ports 11 come within the cylinder, upon which air passes from the cylinder into the valve and 80 from both ends thereof to the reservoir. As the piston nears the end of its downstroke, the valves are moved, valve 5 up and valve 6 down, closing both the inlet and outlet ports at or about the instant when the piston 85 has reached the end of its stroke, and when the piston again reaches its mid-stroke the cycle of movements again begins.

Instead of the reciprocatory tubular valves 5 and 6 I may employ stationary valve-casings 15 and 16, as shown in Fig. 4, over which the piston-head reciprocates and within which move the valves 18, which are adjustably secured to the valve-stems 17. These valve-casings are provided within the cylinder with 95 annular bridged ports 19, and the valves are actuated in a similar manner to those above described, the operation being substantially similar. I prefer, however, the form of Fig. 1, because all clearance in the cylinder is 100 thereby done away with.

The advantages of my invention will be

apparent to those skilled in the art, since the piston acts to the very end of its stroke, there being no clearance on account of the movement of the tubular valve. The valves are balanced in all positions and move smoothly and uniformly with no pounding and require little power to be exerted thereon, while all their movements are positive and not dependent either upon the air or upon weights or springs.

The reciprocating valve-tubes might be closed at the ends, and many other changes may be made without departing from my invention, since I consider myself the first to provide a valve which passes through the piston and cylinder heads, the word "valve" being used in its broad sense, whether consisting of a movable tube, as in Fig. 1, or a stationary tube and inner moving port, as in Fig. 4, as well as the first to employ the tubular valve in the combination recited in my last claim;

I claim—

1. A cylinder having a moving piston or plunger-head, a valve extending through the piston-head and through the cylinder-heads and means independent of the piston for actuating the valve; substantially as described.
2. A cylinder having a piston or plunger head, and tubular inlet and outlet valves extending through said piston-head; substantially as described.
3. A cylinder having a piston or plunger head, tubular inlet and outlet valves extending through said piston-head, and means for

reciprocating said valves; substantially as described.

4. A cylinder having a piston or plunger head, tubular valves having ports in their sides and extending through the piston-head, and means for reciprocating said valves independently of the piston-head; substantially as described.

5. A cylinder having a piston or plunger head, tubular inlet and outlet valves extending through said piston head, and means for reciprocating said valves, the outlet valve being arranged to open after the piston has moved a part of its stroke; substantially as described.

6. A cylinder having a piston or plunger head, and tubular inlet and outlet valves extending through the piston-head and through the cylinder heads; substantially as described.

7. In a pump or compressor system, a cylinder provided with a moving piston, a tubular valve arranged to reciprocate through the cylinder-head, and having side ports, and means for moving the valve so that its ports shall be alternately placed inside and outside said head; substantially as described.

In testimony whereof I have hereunto set my hand.

JULIAN KENNEDY.
